LABELING MACHINE

Samuel E. Morral, Morral, Ohio, assignor of one-half to William W. Morral, Morral, Ohio

Application June 12, 1931, Serial No. 543,911.

17 Claims. (Cl. 216—58)

This invention relates to a labeling machine and is designed more particularly for applying labels to cylindrical cans such as are commonly used for preserving vegetables and fruits.

5 One object of the invention is to provide such a machine which will be simple in its construction and highly efficient in operation at a relatively high speed.

A further object of the invention is to provide 10 improved means for applying paste to the cans as they approach the pile of labels.

A further object of the invention is to provide improved means for applying paste to the uppermost label of the pile.

15 A further object of the invention is to provide means for causing the cans to be delivered to the runway one at a time and in proper spaced relation.

A further object of the invention is to provide 20 a machine of this character which is adjustable to accommodate it to cans and labels of different sizes.

Other objects of the invention will appear as the machine is described in detail.

25 In the accompanying drawings Fig. 1 is a side elevation of a machine embodying my invention; Fig. 2 is a plan view of the same; Fig. 3 is a longitudinal sectional view taken centrally of the machine; Fig. 4 is a transverse section taken 30 on the line 4—4 of Fig. 1; Fig. 5 is a transverse section taken on the line 5—5 of Fig. 1; Fig. 6 is a transverse section taken on the line 6—6 of Fig. 1, looking in the direction of the arrows; Fig. 7 is a section taken on the line 7—7 of Fig. 35 2; and Figs. 8 and 9 are sectional views on the line 8—8 of Fig. 7 on a larger scale.

In these drawings I have illustrated one embodiment of my invention and have shown the same as comprising a main frame 10 mounted on 40 legs 11 and supporting a runway which extends for substantially the full length thereof. The forward portion of this runway comprises a pair of track members 12 and the rear portion of the runway comprises a flat supporting member 13 which may, if desired, be provided with a yieldable surface, such as a rubber mat 14. The adjacent ends of the portions 12 and 14 of the runway are spaced apart and this intermediate portion of the runway is formed by the upper edges 45 of the side members of a label supporting device, as will be hereinafter described. Suitable means are provided for moving the cans lengthwise of the runway and this means preferably comprises an endless conveyor which is here shown as consisting of two sprocket chains 15 which extend

about sprocket wheels 16 carried by a shaft 17 at the forward end of the machine and about sprocket wheels 18 carried by a shaft 19 at the rear end of the machine. The lower stretch of this conveyor extends along the runway and is spaced such a distance therefrom that it will engage the cans on the runway and roll them along the same. Preferably yieldable pressure rollers 20 are arranged above the lower stretch of the conveyor to hold the same in firm contact with the cans. These rollers are here shown as carried by suitable supporting members 21 slidably mounted in a supplemental frame 22 supported on the main frame by standards 23. Ordinarily the weight of the rollers and the supporting 15 structures will provide the necessary pressure but, if desired, suitable means may be provided for increasing this pressure, such as weights 24. One of the conveyor shafts is connected with a suitable source of power and, as here shown, the 20 forward shaft 17 is provided with a sprocket wheel 125 by means of which it may be connected with a motor. Guide bars 25 and 26 are arranged above and along the respective sides of the runway to engage the ends of the cans and properly 25 position them on the runway. Preferably one of these guide bars is slideable so that it will exert a light pressure on the end of the can and press the other end thereof against the other guide bar. For this purpose the guide bar 25 is carried by rods 27 slidably mounted in the standards 23 and is acted upon by springs 28. To accommodate the guide bars to cans of different lengths the bar 26 is carried by rods 29 30 slidably mounted in the adjacent standards 21 35 and secured in adjusted positions therein by set screws 30.

The cans are delivered to the runway by means of an inclined chute 31 and are discharged over a second inclined chute 32. The delivery of the 40 cans from the chute to the runway is so controlled as to cause the can to be delivered one at a time and at properly spaced intervals. In the present construction the controlling means comprises a pulley or drum 33 which is carried by a shaft 34 mounted in the outer ends of a pair of arms 35 which are pivotally mounted on the shaft 17. A belt 36 extends about the drum 33 and about a second pulley or drum 37 secured to the shaft 17. The arrangement is such that 45 the drum 33 will be located normally in the path of the cans on the chute 31 and its position may be regulated by means of adjustable stops, such as screws 38 carried by the arms 35 and engaging the supplemental frame 22, on which the shaft 50 55

17 is mounted. As the cans move down the inclined chute the foremost can will engage the belt on the drum 33 and its movement will be retarded but the frictional contact of the belt 5 with the can will move the same beneath the drum 33, the latter rising to permit the passing of the can and when the can has passed the drum it will roll by gravity onto the runway. The drum is operated in timed relation to the movement of the main conveyor so as to cause the cans to be delivered thereto at the proper intervals. As here shown the drum 33 is of a diameter considerably greater than the diameter of the drum 37 so that the belt and the drum 33 move at a speed somewhat less than the speed of the main conveyor.

Arranged beneath the runway and between the ends thereof is a suitable structure for supporting a pile of labels with the uppermost label in a position to be engaged by a can on the runway. This structure is here shown as a housing comprising fixed end walls 39 and 40 and fixed side walls 41 and 42. Extending through the bottom of the housing is a plunger 43 having at its upper 25 end a head or platform 44 on which the pile of labels, 45, rests. The lower end of this plunger is connected with one end of a lever 46 which is pivotally mounted on a bracket 47 depending from the main frame and is acted upon by a spring 48 which tends to move the plunger and the labels upwardly, the upward movement of the labels being limited, as will be hereinafter described. To accommodate this label supporting structure to labels of different sizes it may be provided with supplemental and adjustable 30 side and end members. The supplemental side member, see Fig. 5, comprises a plate 49 carried by a bar 50 which extends through the fixed side wall 42 and may be secured in adjusted positions 35 with relation thereto by a thumb screw 51 which extends over a bracket 52 having a slot 155 on the fixed side wall. The adjustable end member comprises a relatively narrow plate 53 carried by a bar 54 extending through the fixed end wall 40 and having a slot 55 to receive a bolt 56 by 40 means of which it may be secured to a bracket 57 on the fixed side wall. Thus these adjustable side and end members may be so positioned with 45 relation to the opposed fixed side and end members as to accommodate labels of various sizes. The upper edges of the fixed side member 41 and the adjustable side member 49 constitute portions 50 of the runway and serve to support the can as it moves over the pile of labels. If desired, the space between the fixed end wall 40 and the adjustable end member 53 may be bridged by bars 55. The forward portions of the edges of the side members are cut away or depressed so that they are substantially flush with the surface of 60 the uppermost label, thus permitting a can supported on those edges to engage the uppermost label. The rear portions of these edges project above the uppermost label, as shown at 59, for a purpose which will hereinafter appear. The upward movement of the pile of labels is limited by 65 a stationary part of a paste applying device, which is indicated as a whole at 60, and a short lip 61 carried by the adjustable end member 53 overlaps the forward end of the uppermost label 70 on the pile.

The tracks 12 forming the front portion of the runway are in the form of plates of sufficient width to accommodate cans of varying lengths but are spaced apart a distance sufficient to receive 75 between them a suitable device for applying

paste to the can as it moves along the runway. As here shown, this paste applying device comprises a roller 62 mounted in a paste receptacle 63 arranged beneath the tracks and provided with a hopper 164 by means of which paste may be delivered thereto. The roller 62 projects upwardly between the tracks 12 to a point slightly above the surfaces thereof so that it will be engaged by and will apply paste to a can passing over the tracks. This roller may be of any suitable character and, in the present instance, it comprises a series of disks secured to a shaft 64 and spaced apart lengthwise thereof by means of spacing collars 65. The shaft is mounted in the side walls of the receptacle 63 and extends laterally from that receptacle through a bearing 66 and is provided beyond that bearing with suitable means for rotating the same, such as a sprocket wheel 67. The paste applying roller 62 is spaced from the forward edge of the pile of labels 45 such a distance that a can will make substantially one complete rotation as it moves from the paste applying roller to the pile of labels, thus causing that portion of the can to which the paste has been applied to engage the forward portion of the uppermost label. For the purpose of accommodating the paste applying device to cans of different sizes and labels of different lengths the roller is mounted for adjustment toward and from the pile of labels and, in the present instance, the paste receptacle 63 is mounted for movement lengthwise of the machine. For this purpose the receptacle is carried by a sub-frame 68 which is mounted upon the side members of the main frame 10 and may be secured in adjusted positions thereon by screws 69 which pass through slots 70. The bearing 66 is carried by this sub-frame and is adjustable therewith and the adjacent side member of the main frame is slotted, as shown at 70, to permit the receptacle and the shaft to be moved lengthwise thereof. The sub-frame is open at its bottom to permit the receptacle to be inserted in and removed from the same and suitable fastening devices, such as clips 71, are attached to the sub-frame to support the receptacle therein. The driving mechanism for the paste applying roller is of such a character that it will accommodate itself to the various positions to which the receptacle and roller may be adjusted. As here shown, a sprocket chain 72 extends about a sprocket wheel 73 on the shaft 17 and about a second sprocket wheel 74 arranged below the paste receptacle and the intermediate portion of that sprocket chain is in operative engagement with the sprocket wheel 67 on the roller shaft. The lower sprocket wheel 74 is carried by an arm 75 which is pivotally mounted on lugs 76, depending from the sub-frame 68, by means of a bolt 77 by means of which the arm and sprocket wheel 74 may be secured in adjusted positions.

Paste is applied to the rear portion of the uppermost label and as the can passes from the paste applying roller 62 over the pile of labels it picks up the forward edge of the uppermost label, wraps 65 the label about itself and then withdraws the rear portion of the label from the paste applying device and causes the pasted end thereof to overlie the front end of the label, thus completing the application of the label to the can. The means 70 for applying the paste to the rear portion of the label can take various forms and is arranged as a whole as indicated at 60 on Fig. 3. This paste applying device preferably comprises an endless conveyor arranged to receive paste from a suit- 75

able source of supply, as by passing the same through a paste receptacle, and to move across the label and thus carry the paste into engagement with the label and distribute the same across the width of the label. The conveyor is formed of metal, or equivalent material, and is of such a character that it may be positively driven so as to prevent the slipping thereof. The outer surface of the conveyor is roughened, or provided with cavities, and as the conveyor passes through the paste receptacle this roughened surface will take up a quantity of the paste, portions of which will project beyond the surface of the conveyor and will be applied to the label as the conveyor moves across the same, thus insuring the application of a proper amount of paste to each label. Such a conveyor may conveniently comprise a plurality of parts so connected as to impart the necessary flexibility to the conveyor and arranged to provide spaces between the parts to receive the paste. If desired, a tubular guideway may be provided through which the conveyor will travel, the guideway having an opening or openings to permit of the application of the paste to the label. In the particular construction here shown this paste applying device comprises a tubular member 78 which extends across the runway and has its lower surface arranged to engage the uppermost label, the lower wall of the tubular member having a series of openings 79 through which paste may pass therefrom into contact with the label. One end of this tubular member projects laterally from the runway and opens into a paste receptacle 80 in which is mounted a sprocket wheel 81. A sprocket chain 82 extends about the sprocket wheel 81 and through the tubular member, thence through a curved guide 83, which communicates with the opposite end of the tubular member, and back above the runway to the sprocket wheel 81. The links of the sprocket chain will carry paste from the receptacle 80 through the tube and deliver the same through the openings 79 onto the uppermost label. Preferably the lower portion of the tube is provided with means for directing the paste through the openings and, as here shown, the forward edges of those portions of the tube which lie in the rear of the respective openings 79 are bent upwardly, as shown at 84, and lie close to the sprocket chain so that they will remove paste therefrom and direct the same through the openings and also permit the paste to pass beneath those portions of the tube between the openings so that paste will be applied across substantially the entire width of the label. The sprocket wheel 81 may be driven in any suitable manner. As here shown, it is mounted on a shaft 85 journaled in the paste receptacle 80 and connected by a flexible joint 86 with a second shaft 87 which in turn is connected by beveled gears 88 with the shaft 64 which carries the paste applying roller 62. If desired, means may be provided for moving the label out of contact with the lower portion of the tubular member so as to prevent the paste from being scraped off the same as the label is withdrawn. For this purpose I have mounted just in the rear of the tubular member 78 a bar 89 which is capable of vertical movement with relation to the tubular member and the lower edge of which engages the uppermost label of the pile. When this bar is in its normal position, see Fig. 8, its upper edge projects above the tubular member and above the runway into the path of a can on the runway so that as the can passes above the tubular member the bar will be

forced downwardly and depress the pile of labels, against the action of the spring 48, and thus move the uppermost label out of engagement with the tubular member 78, see Fig. 9. As soon as the can has passed the labels will be returned to their normal positions with the uppermost label in contact with the paste applying tube 78. As has been heretofore stated, the rear portions of the edges of the side members of the label supporting structure, which constitute parts of the runway, project above the pile of labels and thus guide the can above the paste applying tube 78. Mounted on these upwardly projecting edges are holding fingers 90 which have their ends turned inwardly above the uppermost label and act on the same in a well known manner.

While I have shown and described one embodiment of my invention I wish it to be understood that I do not desire to be limited to the details thereof as various modifications may occur to a person skilled in the art.

Having now fully described my invention, what I claim as new and desire to secure by Letters Patent, is:

1. In a labeling machine, a runway, means for moving a can over said runway, means for supporting a pile of labels beneath said runway with the uppermost label adjacent thereto, means in advance of said pile of labels for applying paste to said can, a paste applying device arranged above the rear end of said pile of labels and normally engaging the uppermost label, and means controlled by the can on said runway to depress said pile of labels as said can moves over said paste applying device.

2. In a labeling machine, a runway, means for moving a can over said runway, means for supporting a pile of labels beneath said runway with the uppermost label adjacent thereto, means in advance of said pile of labels for applying paste to said can, a tubular member arranged above the rear end of said pile of labels with its lower wall normally in contact with said uppermost label and having openings through said lower wall, means for delivering paste through said tubular member to said uppermost label, and a member movably mounted adjacent to said tubular member with its lower portion in contact with said uppermost label and its upper portion in the path of a can on said runway, whereby the movement of said can past said tubular member will cause said movable member to depress said pile of labels.

3. In a labeling machine, a runway, means for moving cans along said runway, means for supporting a pile of labels beneath said runway with the uppermost label in the path of a can on said runway, means in advance of said supporting means for applying paste to a can on said runway, and a paste applying device supported above said pile of labels and comprising a conduit engaging the uppermost label and having openings in the engaging wall thereof, and an endless conveyor for moving paste through said conduit and delivering the same to said openings.

4. In a labeling machine, a paste applying device comprising a tubular conduit having an opening in one wall thereof, and a paste feeding device mounted in said tubular conduit for movement lengthwise thereof.

5. In a labeling machine, a paste applying device comprising a paste receptacle, a tubular member connected at one end with said receptacle and having an opening in one wall thereof, and an endless conveyor extending through said

- paste receptacle and through said tubular member.
6. In a labeling machine, a paste applying device comprising a paste receptacle, a tubular member connected at one end with said receptacle and having openings in one wall thereof, and an endless conveyor extending through said paste receptacle and through said tubular member, said wall of said tubular member having parts adjacent to said opening to divert the paste from said conveyor to said openings.
7. In a labeling machine, a paste applying device comprising a tubular member having openings in one wall thereof, a paste receptacle communicating with said tubular member, and an endless conveyor movable through said tubular member to convey paste from said receptacle to said openings, those portions of the wall of said tubular member which lie between adjacent openings being bent upwardly to form an inwardly extending lip in the rear of each opening.
8. In a labeling machine, a paste applying device comprising a paste receptacle, a tubular member communicating at one end with said receptacle and having an opening in one wall thereof, a sprocket wheel supported in said paste receptacle, a curved guide communicating with the other end of said tubular member, and a sprocket chain extending about said sprocket wheel, through said tubular member and about said guide.
9. In a labeling machine having means for supporting a pile of labels in a position to be engaged by a can moving through said machine, a paste receptacle, a conduit leading from said receptacle to said pile of labels, and a conveyor movable lengthwise through said receptacle and said conduit and across the uppermost label of said pile to deliver paste to said label.
10. In a labeling machine having means for supporting a pile of labels, a source of supply of paste, an endless metallic conveyor communicating with said source of supply and movable longitudinally across the outer label of said pile, said conveyor having a roughened surface to receive the paste and move the same into engagement with the label as said conveyor travels across said label, and means for positively driving said conveyor.
11. In a labeling machine having means for supporting a pile of labels, a source of supply of paste, an endless metallic conveyor communicating with said source of supply and movable longitudinally across the outer label of said pile, said conveyor comprising a plurality of connected parts arranged to provide spaces between said parts to receive the paste and move the same into engagement with the label as the conveyor travels across said label, and means to drive said conveyor.
12. In a labeling machine, a paste receptacle, an endless conveyor movable through said receptacle and across the outer label of said pile, that side of said conveyor which is adjacent to said label having cavities to receive the paste and distribute the same across the label as said conveyor travels over said label, and means for actuating said conveyor.
13. In a labeling machine, a paste receptacle, a label holder to support a pile of labels, a conveyor movable lengthwise through said receptacle and across the outer label of said pile of labels to convey paste from said receptacle and distribute the same on said label as said conveyor moves across said label, said conveyor having a longitudinal series of openings, and a toothed wheel to drive said conveyor.
14. In a labeling machine, a paste receptacle, a sprocket chain movable lengthwise through said receptacle and across the outer label of said pile to convey paste from said receptacle and distribute the same on said label as said chain travels across said label, and a sprocket wheel to drive said sprocket chain.
15. In a labeling machine having means for supporting a pile of labels, a source of supply of paste, an endless metallic conveyor communicating with said source of supply and movable longitudinally across the outer label of said pile, said conveyor having a roughened surface to receive the paste and move the same into engagement with the label as said conveyor travels across said label, means arranged between said conveyor and said label to positively separate portions of the paste from the roughened surface of said conveyor, and means for driving said conveyor.
16. In a labeling machine, having means for supporting a pile of labels, a source of supply of paste, an endless metallic conveyor communicating with said source of supply and movable longitudinally across the outer label of said pile, said conveyor being adapted to receive paste and move the same into engagement with said label as said belt travels across said label, and means for positively actuating said metallic conveyor.
17. In a labeling machine, a runway, means for moving a can along said runway, means for supporting a pile of labels beneath said runway with the uppermost label adjacent to the path of the can on said runway, a paste receptacle mounted beneath said runway in advance of said pile of labels for adjustment toward and from said pile of labels, a shaft journaled in said receptacle and extending beyond one side thereof, a roller carried by said shaft within said receptacle and projecting into the path of a can on said runway, driving mechanism for said roller comprising sprocket wheels arranged on opposite sides of said shaft, one of said sprocket wheels being supported by said receptacle and being adjustable toward and from the other sprocket wheel, a sprocket chain extending about said sprocket wheels, and a sprocket wheel mounted on the outer end of said roller shaft and engaging an intermediate portion of said sprocket chain.

SAMUEL E. MORRAL.
